Patented Mar. 16, 1976

239,213

BAKERY TRAY OR THE LIKE

James C. Carroll, Bartlesville, Okla., assignor to Phillips
Petroleum Company, Bartlesville, Okla.

Filed July 29, 1974, Ser. No. 492,832

Term of patent 14 years

Int. Cl. D3—02

U.S. Cl. D87—1 R

FIG. 2

FIG. 3

FIG. 4

FIG. 5

FIG. 6

FIG. 7

FIG. 8

FIG. 1 is a top perspective view of a bakery tray or the like showing my new design;

FIG. 2 is a top plan view;

FIG. 3 is a side elevational view taken from the lower, outer, left side of FIG. 1.

FIG. 4 is a side elevational view taken from the lower, outer, right side of FIG. 1.

FIG. 5 is a side elevational view taken from the upper, outer, right side of FIG. 1.

FIG. 6 is a side elevational view taken from the upper, outer, left side of FIG. 1.

FIG. 7 is an enlarged sectional view taken on the line 7-7 of FIG. 6; and

FIG. 8 is an enlarged sectional view taken on the line 8-8 of FIG. 4.

I claim:

The ornamental design for a bakery tray or the like, as shown and described.
